CLAIM

The ornamental design for an osteotome blade, as shown and described.

DESCRIPTION

FIG. 1 is a top perspective view of an osteotome blade in accordance with the new design;

FIG. 2 is a top plan view of the osteotome blade of FIG. 1; FIG. 3 is a bottom plan view of the osteotome blade of FIG. 1;

FIG. 4 is a right side elevational view of the osteotome blade of FIG. 1;

FIG. 5 is a left side elevational view of the osteotome blade of FIG. 1;

FIG. 6 is a front elevational view of the osteotome blade of FIG. 1; and,

FIG. 7 is a rear elevational view of the osteotome blade of FIG. 1.

The broken lines, and unshaded surfaces bound by broken lines, illustrate portions of the osteotome blade which form no part of the claimed design.

1 Claim, 3 Drawing Sheets
